UNITED STATES PATENT OFFICE.

ARTHUR U. TILLER, OF RICHMOND, VIRGINIA.

LOCOMOTIVE DRAFT AND STOKER CONTROLLING SYSTEM.

Application filed January 4, 1922. Serial No. 526,961.

To all whom it may concern:

Be it known that ARTHUR U. TILLER, a citizen of the United States, residing at Richmond, in the county of Henrico and 5 State of Virginia, has invented certain new and useful Improvements in Locomotive Draft and Stoker Controlling Systems, of which the following is a specification.

This invention relates to draft and stoker 10 regulating apparatus for railway locomotives and particularly to an automatic control system for the same.

The details and objects of the invention will appear as described in connection with 15 the accompanying drawings and hereinafter set forth and claimed.

In the drawings forming a part of this specification, like characters of reference are used to designate the same parts in the five 20 figures in which,—

Figure 1 is a diagrammatic side elevation of a locomotive boiler partly in section, disclosing a control system in accordance with this invention,

25 Figure 2 is a fragmentary side elevation on an enlarged scale showing the steam-dome of the locomotive and a portion of the system,

Figure 3 is an enlarged vertical sectional view of a cylinder for operating the dampers in the smoke-box of the locomotive, and

30 Figures 4 and 5 are side elevations partly in section of fluid pressure operated valves 35 adapted for use in the system.

Referring to the drawings, the system comprising the subject matter of this invention is shown as being applied to a locomotive, the boiler 10, of which is represented 40 in Figure 1; the steam-dome 11 has the usual steam pipe 12 for supplying steam to the engine cylinders, and steam is supplied to the cab by means of a steam pipe 13.

In the preferred arrangement, the smoke-box 14 has a partition directing the combustion gases down through a grating damper 15; from there the gases pass around the exhaust pipe 16 for the steam from the engine cylinders and an atmosphere draft tube 17 which is arranged to extend upwardly and surround the exhaust pipe 16. The gases then pass up through the netting 18 and out the smoke-stack 19 as generally designated by the series of arrows.

55 The damper 15 is represented as being composed of a series of pivoted bars 20

connected by short links 21 with an arm 22 which in turn is attached to the lower end of a rod 23. The upper end of rod 23 is connected to a bell-crank lever 24 and an operating arm 25 attached to the other end of the crank is adapted to shift the bars 20 from closed to partly open and open positions.

The draft tube 17 extends from the bottom of the smoke-box up to a position about the same height as the exhaust pipe 16, and is adapted to direct a current of atmosphere up through the smoke-stack. At the lower end of the tube 17 is a damper 26 which 60 is connected by means of a rod 27 and bell-crank 28 with the operating arm 25 for operating it.

Connections of the dampers 15 and 26 with the arm 25 are such that when the damper 15 is open damper 26 is closed and when damper 26 is open damper 15 is closed, or the dampers are both partly open for one 70 operation of the arm. A cylinder 29 for operating a lever 30 connected with the arm 25 is adapted to operate the dampers in the manner set forth.

The cylinder 29 which is represented on a larger scale in Figure 3, encloses a piston 31 having a connecting rod 32 extending 75 therefrom for raising lever 30. Steam is admitted through a pipe 33 into the bottom of the cylinder. At the side of the cylinder is a by-pass 34 having its lower port 35 arranged about half-way up the cylinder, at 80 a height such that the dampers will be operated to their partly open positions, and the upper port 36 opens into the cylinder above the top of the piston. Any suitable type of

85 fluid pressure operated valve 37 is placed in the by-pass for closing it so that steam entering the cylinder 29 will force the piston to the top of the cylinder; the cylinder may be provided with a leak port so as to 90 allow the rapid escape of steam upon the 95 closing of valve 37. Valve 37 is connected to a steam pipe 39 so that whenever there is steam pressure in pipe 39 the valve will cut off the by-pass and will flow through a check valve 40 in the direction indicated 100 and force the piston to the top of its stroke,—closing damper 15 and opening damper 26. However, when steam pressure is supplied by pipe 41 alone, the by-pass is 105 open and the piston 31 will ascend so as to 110 open port 35, then there will be an equalization of steam pressure on the two sides of

the piston and it will be maintained in the partially raised position, and thus maintain the dampers 15 and 26 in their intermediate position as disclosed in the various figures of the drawings. The closing of valve 37 by steam pressure in pipe 39 will cause the piston to ascend from either of its lower positions to the top of its stroke.

Connected with the steam-dome by a pipe 42 is a pop valve governor 43 which is set to pass steam pressure into pipe 39 at a pressure slightly below the maximum pressure allowed in the boiler. Thus when the steam pressure in the boiler is excessive it 15 operates to close valve 37 and force the piston 31 to its uppermost position closing damper 15 (i. e. to a position to cut the draft through the fire-box and tubes to a minimum), and opening damper 26 so as to prevent the boiler pressure reaching the popping off point. Steam pressure in pipe 39 passes also into pipe 44, through a check valve 45 in a connection 46 (which may be omitted) between pipes 39 and 44, or after 20 passing check valve 40 it can pass through pipes 41 and 47 into pipe 44. This operates on a fluid pressure operated valve 48 for cutting off the flow of steam through pipe 49 to a stoking engine (not shown). 25 This valve is also closed when steam pressure is admitted through pipe 41 for operating the dampers to their intermediate positions, as steam pressure is not required to be kept up when the locomotive is motionless or drifting, and there can be an economizing of fuel at these times as well as when the pressure is excessive.

The pop valve governor 43, heretofore referred to, is shown in detail in Figure 2 40 and comprises a small pop valve 50 connected with the feeder pipe 42 and a plunger valve 51. A connection 52 between the pop valve 50 and a cylinder 53 of valve 51 admits the exhaust from the pop valve into the cylinder forcing the piston 54 with the valve plunger 55 down against the tension of spring 56 opening the passage so as to admit steam into pipe 39. The pop valve may be set so as to open at any desired 45 pressure, but of course it is preferably set so as to operate at as high a pressure as possible so that it will go off at a pressure slightly less than that at which the locomotive pop valve 78 exhausts, as its main 50 purpose is to prevent the steam pressure from rising to the popping off pressure.

Steam for operating the stoking engine is supplied from the steam pipe 13 to the pipe 49 heretofore referred to. A valve 57 60 is normally used to regulate the operation of the stoking engine and may be set as desired, and the valve 48 comes into action for cutting the steam to the stoking engine off automatically whenever there is steam 65 pressure in pipe 44. A steam pipe 58 ex-

tending forwardly of the locomotive is supplied with steam from pipe 13 and may be cut off and regulated by means of a suitable hand valve, such as a globe valve 59, by the engineer in the cab. A blower pipe 70 75 is also supplied with steam from pipe 13, and by opening the valve 61, steam is admitted thereto and operates a suitable blower such as a nozzle 62 in the smoke-box adjacent to the stack.

Steam pipe 58 is connected with the pipe 41 which leads to the cylinder 29 for operating the dampers 15 and 26 to their intermediate positions and closing valve 48 in the steam supply pipe to the stoker, also 80 for supplying steam to the blower 62 for a limited time as hereinafter set forth.

A fluid pressure operated valve 63, as shown in Figure 4, is connected in pipe 58. This valve comprises a plunger 64 and piston 65 in a cylinder 66 adapted to be closed by steam pressure in the cylinder working against a spring 64'; the piston 65 is provided with a leak port 65' which will allow it to return to its normal position as quickly 90 as possible when the steam pressure behind it is cut off. The valve shown in the drawings for purpose of disclosure is a preferred form and is substantially the same as valves 37 and 48 and similar in construction to 95 valve 51 which opens by fluid pressure instead of being closed thereby. Steam pressure is supplied to valve 63 through a pipe 67 connected therewith and with the steam pipe 12 which leads from the throttle valve 100 68 in the steam-dome to the engine cylinders (not shown). Thus, whenever the throttle valve 68 is open, steam pressure operates to close valve 63 thereby fully 105 opening damper 15, closing damper 26 and allowing valve 48 to open for passing steam pressure to the stoking engine.

A second fluid pressure operated valve 69 is connected in pipe 58 adjacent to the blower 62. This valve, as shown in the detail, Figure 5, is similar to valve 51 and is adapted to be opened by fluid pressure. Steam for opening this valve is supplied through pipe 70 which is connected with pipes 60 and 71 for receiving steam pressure from the blower pipe upon opening of valve 61 or from pipe 67 during the time the throttle 110 68 is open. The piston 72 for opening this valve is provided with a small leak port 73 which may be adjusted so as to maintain the valve open for a predetermined time after shutting off the steam pressure in pipe 70, and a check valve 74 maintains the steam in the cylinder. Check valves 75 and 76 115 in pipes 67 and 70 respectively are provided for preventing steam from passing from one of the pipes to the other, and will permit the operation of both fluid pressure valves 63 and 69 by steam pressure from either source. A check valve 77 in pipe 58 prevents steam 120 125 130

from pipe 60 from operating the piston in cylinder 29 and closing valve 48.

In the operation of the system, while the locomotive is standing still, steam pressure in the pipe 58 passes through valve 63 into cylinder 29 and maintains the dampers in their intermediate positions, and operates valve 48 to shut off the steam supply from pipe 13 through pipe 49 to the stoking engine. Upon opening the throttle valve 68 to start the engine the steam pressure passing through pipes 12 and 67 closes valve 63 cutting off steam in pipe 58 and allowing valve 48 to open and piston 31 in cylinder 29 to drop to its lowest position so as to open damper 15 and close damper 26. The cylinder of valve 69 is immediately charged with steam through pipes 71 and 70 and opens for steam to pass through pipe 58 to the blower 62 for a short interval after valve 63 is again opened by closing the throttle 68 when the locomotive is drifting or stopped. Thus the blower 62 starts to operate and operates for a time while valve 69 is held open by the fluid pressure and until the valve closes due to the escape of the fluid through the leak port 73 in piston 72, after the shifting of the dampers, to cause a draft up the smoke-stack so as to draw the combustion gases from the boiler tubes and force them out the stack until the fire has cooled down some; these hot gases would otherwise have detrimental results in returning through the fire tubes and fire box which is overcome by the operation of the blower in this manner.

At any time the engineer desires to fire up, he supplies steam to the blower by opening valve 61. Steam pressure in pipe 60 closes valve 63 and opens valve 69 in the same manner that the opening of the throttle valve 68 does. The damper 15 is opened and 26, closed, valve 48 is opened for operating the stoking engine and the blower 62 is operated at the same time. The closing of valve 61 shifts the dampers, operates valve 48, and allows steam to pass from pipe 58 to the blower 62 until valve 69 closes.

In case the boiler pressure should reach too great a pressure at any time, the pop valve 50 will open valve 51, and steam pressure passing through pipes 39 and 44 will close damper 15, open damper 26 and shut off the steam supply to the stoking engine through valve 48 until the pressure of the boiler has decreased below the critical pressure and prevent the locomotive from popping off.

The many advantages of the herein described invention will readily suggest themselves to those skilled in the art to which it appertains.

It is to be understood that the invention relates to a system which employs fluid pressure in parts, and various devices set

forth, and is not limited to the exact details of construction shown and described, and that the disclosures in the drawings is for the purpose of illustrating one preferred embodiment thereof, as it is manifest that various changes may be made in the exact constructions and particular arrangements of parts without departing from the spirit of the invention, hence the right is reserved to make such changes, or modifications, as may fairly fall within the scope of the appended claims when fairly construed.

What is claimed as the invention, and is desired to be secured by Letters Patent is:

1. In combination with the smoke box of a locomotive having an exhaust pipe for steam from the engine cylinders therein and a smoke-stack, a draft tube extending upwardly from the bottom of the smoke box and surrounding said exhaust pipe, a damper at the lower end of said tube, and means for maintaining the damper closed and for opening it for allowing a current of atmosphere to enter and pass upwardly through the smoke-stack.

2. In combination with a smoke box of a locomotive having a smoke-stack extending above it, a damper in the entrance to the smoke box from the boiler fire tubes, and a second damper to a passage in the bottom of the smoke box forward of the first said damper for allowing a current of air to enter and pass through the stack.

3. In combination with a smoke box of a locomotive having a smoke-stack extending above it, a damper in the entrance to the smoke box from the boiler fire tubes, a second damper to a passage in the bottom of the smoke box forward of the first said damper for allowing a current of air to enter and pass through the stack, a connection between the two dampers whereby when one damper is fully opened the other is closed, and means for operating said dampers.

4. In combination with a boiler and smoke box of a locomotive, a damper between the boiler tubes and the smoke box, a damper for an air draft passage in the smoke box, fluid pressure means for operating the dampers for opening one and closing the other, and fluid pressure means for operating both dampers to an intermediate position.

5. In combination with a boiler and smoke box of a locomotive, a damper between the boiler tubes and the smoke box, a damper for an air passage in the smoke box, means for opening the damper between the boiler tubes and smoke box and closing the damper in the air draft passage when the engine throttle is opened, and means for shifting said dampers when said throttle is closed.

6. In combination with a boiler and smoke box of a locomotive, a damper between the boiler tubes and the smoke box, a

damper for an air passage in the smoke box, means for opening the damper between the boiler tubes and smoke box and closing the damper in the air draft passage when the engine throttle is opened, means for shifting said dampers when said throttle is closed, and manually operated means for opening the first named damper and closing the second damper during the time when said throttle is closed.

7. In combination with a boiler and smoke box of a locomotive, a damper between the boiler tubes and smoke box, a damper for an air passage in the smoke box, means for opening the damper between the boiler tubes and smoke box and closing the damper in the air draft passage when the engine throttle is opened, means for shifting said dampers when the throttle is closed, and means for closing the first named damper and opening the second damper at any time during the operation of the boiler when the steam pressure therein becomes excessive.

8. In combination with a boiler and smoke box of a locomotive, a damper between the boiler tubes and smoke box, a damper for an air passage in the smoke box, means for opening the damper between the boiler tubes and smoke box and closing the damper in the air draft passage when the engine throttle is opened, means for shifting said dampers when the throttle is closed, means for closing the first named damper and opening the second damper at any time during the operation of the boiler when the steam pressure therein becomes excessive, and manually operated means for effecting a shifting of the dampers so as to open the first damper and close the second at any time when the boiler is working below an excessive pressure.

9. In a device for shifting dampers, a cylinder having a piston therein, a connection with the bottom of the cylinder for admitting fluid pressure for raising said piston from the lower end of its stroke to an intermediate position and to an upper position, and means for rendering the fluid pressure in the cylinder inoperative for raising said piston above its intermediate position to the upper position of its stroke.

10. In a device for shifting dampers, a cylinder having a piston therein, a connection with the bottom of the cylinder for admitting fluid pressure for raising said piston from the lower end of its stroke to an intermediate position and to an upper position, said cylinder having a by-pass in its side for equalizing the pressure on the two sides of the piston and preventing it from rising above its intermediate position, and fluid pressure means for closing said by-pass so that the piston will be raised to its upper position.

11. In a safety governor for locomotives for regulating the operation of the fire in the boiler, a pop valve and a fluid pressure operated valve connected so as to receive steam pressure from the boiler, and a connection between the discharge of the pop valve and the fluid pressure valve for opening the same for allowing the passage of steam pressure through the valve when the steam pressure exceeds the popping off pressure of the pop valve.

12. In combination with a locomotive, a blower in the smoke box thereof, a steam pipe connected with said blower, a normally open fluid pressure operated valve in said pipe adapted to be closed by steam pressure, a second fluid pressure operated valve in said pipe normally closed and adapted to be opened when steam pressure closes the first named valve, and means for retarding the closing of the second valve for some time after the opening of the first valve for allowing the passage of steam through the pipe to the blower for a limited time.

13. In combination with a locomotive, a blower in the smoke box thereof, a steam pipe connected with said blower, a normally open fluid pressure operated valve in said pipe adapted to be closed by steam pressure, a second fluid pressure operated valve in said pipe normally closed and adapted to be opened when steam pressure closes the first named valve, means for retarding the closing of the second valve for some time after the opening of the first valve for allowing the passage of steam through the pipe to the blower for a limited time, a second steam pipe connected with said blower, a valve in said pipe adapted to be operated in the locomotive cab for allowing the passage of steam to the blower, and a connection from said steam pipe for operating said fluid pressure operated valves.

14. In combination with a locomotive, a blower in the smoke box thereof, a steam pipe connected with said blower, and means for allowing the passage of steam to said blower for a predetermined time after the closing of the engine throttle valve.

15. In combination with a locomotive, a blower in the smoke box thereof, means for rendering said means inoperative during the time the engine throttle valve is open, means for automatically operating the same for a predetermined period after closing the engine throttle valve, and manually controlled means in the locomotive cab for operating said blower.

16. In combination with a locomotive having a steam pipe for supplying steam to a stoking engine, means for cutting off said steam supply to the stoking engine automatically, manually operated means for

- rendering said automatic means inoperative so that steam pressure can be supplied to the stoking engine at any time when the steam pressure in the boiler is not excessive, 5 and a second means for cutting off the steam supply to the stoking engine when the pressure in the boiler is excessive.
17. In combination with a locomotive having a stoking engine, means for controlling the steam supply to the stoking engine automatically controlled by the locomotive throttle, and means for cutting off the steam supply to the stoking engine when the pressure in the boiler is excessive.
18. In combination with a locomotive equipped with draft regulating devices and a stoking engine, a controlling system for automatically controlling the steam supply to the stoking engine controlled by the locomotive throttle, and means operated by said system for controlling the draft regulation.
19. In combination with a locomotive equipped with draft regulating devices and a stoking engine, a controlling system for automatically controlling the steam supply to the stoking engine controlled by the locomotive throttle, means operated by said system for controlling the draft regulation, and means in the system for shutting off the steam supply to the stoking engine and cutting the draft to a minimum when steam pressure in the locomotive boiler is excessive.
20. In combination with a locomotive equipped with draft regulating devices and with a stoking engine, a controlling system for said stoking engine and draft devices operative to supply steam to the stoking engine and give a maximum draft when the locomotive throttle is open and to cut down on the draft and close the steam supply for operating the stoking engine when the locomotive throttle is closed.
21. In combination with a locomotive equipped with draft regulating devices and with a stoking engine, a controlling system for said stoking engine and draft devices operative to supply steam to the stoking engine and give a maximum draft when the locomotive throttle is open, to cut down on the draft and close the steam supply for operating the stoking engine when the locomotive throttle is closed, and to force a draft for a predetermined time following the closing of the engine throttle.
22. In combination with a locomotive equipped with draft regulating devices and with a stoking engine, a controlling system for said stoking engine and draft devices operative to supply steam to the stoking engine and give a maximum draft when the locomotive throttle is open, to cut down on the draft and close the steam supply for operating the stoking engine when the locomotive throttle is closed, and to force a draft for a predetermined time following the closing of the engine throttle.
23. In combination with a locomotive equipped with draft regulating devices and with a stoking engine, a controlling system for said stoking engine and draft devices having means for supplying steam to the stoking engine and giving a maximum draft when the locomotive throttle is open, means for cutting down on the draft and closing the steam supply for operating the stoking engine when the locomotive throttle is closed, means for supplying steam to a draft blower for a predetermined time following the closing of the locomotive throttle, and manually operated means connected with the system supplying steam to the stoking engine and draft blower and opening the drafts to a maximum simultaneously.
24. In combination with a locomotive equipped with draft regulating devices and with a stoking engine, a controlling system for said stoking engine and draft devices having means for supplying steam to the stoking engine and giving a maximum draft when the locomotive throttle is open, means for cutting down on the draft and closing the steam supply for operating the stoking engine when the locomotive throttle is closed, means for supplying steam to a draft blower for a predetermined time following the closing of the locomotive throttle, manually operated means connected with the system for supplying steam to the stoking engine and draft blower and opening the drafts to a maximum simultaneously, and means in the system for cutting off the steam supply to the stoking engine and cutting the draft to a minimum at any time the steam pressure in the locomotive boiler becomes excessive.
25. In combination with a locomotive equipped with draft regulating devices and with a stoking engine, a controlling system for said stoking engine and draft devices having means for supplying steam to the stoking engine and giving a maximum draft when the locomotive throttle is open, means for cutting down on the draft and closing the steam supply for operating the stoking engine when the locomotive throttle is closed, manually operated means connected with the system for supplying steam to the stoking engine and opening the drafts, and means in the system for closing the steam supply to the stoking engine and cutting the draft to a minimum at any time the steam pressure in the locomotive becomes excessive.
26. The herein described method step of an automatic regulation of locomotives comprising the checking of the drafts upon the closing of the engine throttle and operation

6
of a blower in the smoke box thereafter for a predetermined time.

27. In combination with a smoke box of a locomotive, having an air passage leading 5 into it and a smoke-stack extending above it, a damper in the smoke box for controlling the draft through the locomotive boiler,

and a damper for said air passage for allowing a current of air to enter the smoke box forward of the first said damper and pass ¹⁰ through the smokestack.

In testimony whereof he affixes his signature:

ARTHUR U. TILLER.
